FIG. 1 is a top, front, right side perspective view of the fluidic connector;
FIG. 2 is a front elevational view of the fluidic connector;
FIG. 3 is a rear elevational view of the fluidic connector;
FIG. 4 is a right side elevational view, the left side being a mirror image thereof, of the fluidic connector; and,
FIG. 5 is a top plan view of the fluidic connector.
Only the portion of the fluidic connector in solid lines is claimed. The portion of the figures shown in dashed lines forms no part of the claimed invention.
